FOLDABLE COMPARTMENT BOX

Emil Morand, Jersey City, N. J.

Application March 21, 1946, Serial No. 655,929

4 Claims. (Cl. 229—28)

1

This invention relates to an improved construction of plural compartment box adapted to be produced from a flat foldable blank of paper stock of any suitable kind.

The invention has for an object to provide a novel plural compartment box formed from a blank of paper stock which is shaped and scored to provide relatively foldable sections comprising a bottom panel from the respective opposite ends of which extend, in longitudinal sequence, an outer end panel, a top panel and a tuck-in end panel, the latter having side flaps respectively bordering its opposite longitudinal margins, together with side panels extending respectively from the respective longitudinal margins of said bottom panel, said side panels terminate at their respective ends in articulated longitudinal compartment partition members; said blank includes articulated transverse compartment partition members which are detachably connected by perforated or weakened lines with the ends of said tuck-in end panels, whereby, when detached, and upon erection of the box from the blank, the same are adapted to be assembled with the longitudinal compartment members, so as to provide the interior of the box with a plurality of compartments or cells; said longitudinal and transverse compartment members are provided with indenting cooperative slots to permit assembly thereof in intersecting relation.

The invention has for another object to provide a plural compartment box, adapted to be produced from the described blank, which can be separated into two completely closed compartment boxes, each one-half the size of the original box, and to this end, the bottom and side panels are provided with a continuous perforated or weakened line extending across the same intermediate their ends.

The invention has for another object to provide a compartment box, adapted to be produced from the described blank, wherein novel means is provided for interlocking the tuck-in panels with the side panels of the box structure, whereby to retain the box structure in closed condition and against disassembly of its parts, and thus secure against accidental opening of the box.

Other objects of this invention, not at this time more particularly enumerated, will be understood from the following detailed description of the same.

An illustrative embodiment of the invention is shown in the accompanying drawings, in which:

Fig. 1 is a plan view of the cut and scored blank from which the novel box is produced.

2

Fig. 2 is a plan view of the blank with its side panels erected perpendicular to the bottom panel and the associated articulated longitudinal compartment partition members turned over said bottom panel, and with the transverse compartment partition members, which have been detached from the blank, disposed in operative assembled relation with said longitudinal partition members and said side panels; and Fig. 3 is a longitudinal section, taken on line 3—3 in Fig. 2.

Fig. 4 is a top plan view of the completed box in its closed condition; Fig. 5 is a side elevational view of the same; Fig. 6 is a longitudinal sectional view thereof, taken on line 6—6 in Fig. 4; Fig. 7 is a horizontal sectional view thereof, taken on line 7—7 in Fig. 6; Fig. 8 is another horizontal sectional view thereof, taken on line 8—8 in Fig. 6; and Fig. 9 is a side elevational view of the box as divided into two completely closed and separate units of smaller size.

Similar characters of reference are employed in the hereinabove described views to indicate corresponding parts.

Referring to the drawings, the novel plural compartment box of this invention is produced from a blank of suitable paper stock, such e. g. as paste-board, card-board, corrugated paperboard or the like. Said blank is cut and scored to provide the box forming elements which comprise a bottom panel 10 and side panels 11. Said side panels 11 respectively extend from the respective longitudinal margins of said bottom panel 10, and are foldably joined thereto by longitudinal fold line determining scores 12. Extending from each end of each side panel 11 is a longitudinal compartment partition member 13, including a spacer section 14. Each spacer section 14 is foldably joined to an end of a side panel 11 by a transverse fold line determining score 15, and each longitudinal partition member 13 is foldably joined to its spacer section 14 by a similar transverse fold determining score 16. Each longitudinal partition member 13 is provided with a transverse slot 17 which enters thereinto from outer or top margin thereof, at a point substantially midway of the length thereof; said slot being of a length approximating one-half the width or height of the longitudinal partition member. The sides of said slots 17, where they join the outer or top margins of said longitudinal partition members 13, are rounded off to provide flared entrance mouths 18, for purposes herein-after explained. The ends of the outer or top margins of said longitudinal partition members 13 are likewise rounded off, as at 19, also for pur-

poses hereinafter explained. Extending from each end of the bottom panel 10, in longitudinal sequence, are an outer end panel 20, a top panel 21, and a tuck-in end panel 22; the latter having side flaps 23 extending respectively from its longitudinal side margins, and foldably joined thereto by fold line determining scores 24. Each outer end panel 20 is foldably joined to the adjacent end of the bottom panel 10 by a fold line determining score 25; and, similarly, each top panel 21 is foldably joined to the adjacent outer end panel 20 by a fold line determining score 26, and each tuck-in end panel 22 is foldably joined to the adjacent top panel 21 by a fold line determining score 27. Initially and detachably connected with the free end of each tuck-in end panel 22 and its side flaps 23, by a line of weakening perforations 28, is a transverse compartment partition member 29 having side flaps 30 extending respectively from its longitudinal side margins, and foldably joined thereto by fold line determining scores 31. Each transverse partition member 29 is provided with a pair of suitably disposed and spaced slots 32 which enter therein from the bottom margin thereof; said slots being of lengths approximating one half the height of the transverse partition member. The sides of said slots 32, where they join the bottom margins of the transverse partition members, are rounded off to provide flared entrance mouths 33, for purposes hereinafter explained.

If the box, as formed from the above described blank is to be divisible and separable into two completely closed units of smaller size, the blank is provided with a continuous transverse line of weakening perforations 34 extending entirely across the bottom panel 10 and side panels 11 intermediate the ends thereof.

Preparatory to manipulating the blank, whereby to form from the same the novel box structure according to this invention, the transverse partition members 29 with their side flaps 30 are first detached from the blank, ready for application to the box interior. This having been done, the blank is manipulated as follows:

First, the side panels 11 are turned upwardly about the scores 12 to stand perpendicular to the plane of the bottom panel 10, whereupon the articulated longitudinal partition members are turned about the scores 15 and 16 so that the spacer sections 14 extend inwardly from the side panel ends to stand perpendicularly in plane transverse to that of the side panels, with the partition members 13 extending inwardly therefrom over the bottom panel 10 and in spaced planes parallel to the side panels 11, as spaced from the latter by said spacer sections 14. After these parts are thus positioned, the articulated transverse partition members 29—30 are assembled with the longitudinal partition members in box compartment forming relation thereto. Preparatory to such assembly of said transverse partition members 29, the side flaps 30 thereof are turned about the scores 31 to extend at right angles to the plane of the partition members 29, 65 whereafter the latter are positioned with the mouths 33 of their slots 32 downwardly directed, so as to be brought into opposition to the upwardly directed mouths 18 of the slots 17 with which the longitudinal partition members 13 are provided, whereupon said transverse partition members 29 are pushed down into and across the said longitudinal partition members 13 so as to interlockingly intersect the same. It will be obvious that the flared mouths 33 and 18 of the 70

respective slots 32 and 17 will facilitate the described assembling movement of the transverse partition members relative to the longitudinal partition members. Said transverse partition members, as so assembled, are arranged in such position that their side flaps 30 lie contiguous to the side panels 11 and extend outwardly toward the spacer sections 14, with their free perpendicular edges abutting the latter at the junctions thereof with said side panels 11. As thus disposed, said side flaps 30 strongly brace and reinforce the corners of the box structure against collapse or distortion. The opposed free ends of the longitudinal partition members 13, when operatively disposed within the interior of the box as described, are spaced apart for a distance approximating twice the thickness of the paper stock of which the box blank is made, whereby to permit insertion therebetween of the tuck-in end panels 22, as will presently appear.

The box, as thus far formed, provides an interior structure comprising a plurality of compartments or cells ready to be packed with a desired content and then closed. To close the box, the foldably related arrangement of parts comprising an outer end panel 20, a top panel 21, and a tuck-in end panel 22, which arrangements extend respectively from the opposite ends of the bottom panel 10, are manipulated. Preparatory to such manipulation, the side flaps 23 of the tuck-in end panels 22 are turned inwardly about the scores 24 to extend at right angles to the plane of said tuck-in end panels. To bring the closure parts into box closing position, the outer end panels 20 are swung upwardly about the scores 25 to stand perpendicular the bottom panel 10 and across the box ends contiguous to the spacer sections 14 of the longitudinal partition members 13, whereupon the associated top panels 21 and tuck-in end panels 22 are in-turned respectively about the scores 26 and 27 so as to direct the free ends of said tuck-in end panels toward the middle of the box interior, for entrance into the space between the opposed ends 45 of the longitudinal partition members 13. To permit a relative angular disposition of the tuck-in end panels and top panels which will facilitate disposition and direction of the free ends of the former for entrance into the box interior between opposed ends of said longitudinal partition members 13, the inner ends of the side flaps 23 are cutaway to provide oblique end portions 23'. The opposed rounded end portions 19 of the longitudinal partition members 13, also provide flared entrance mouths leading into the box interior whereby to further facilitate insertion of said tuck-in end panels 22. Said tuck-in end panels 22 are pushed down into the box interior so as to lie face to face and in perpendicular transverse plane intermediate the opposed sets of longitudinal partition members 13, and with their side flaps 23 disposed to lie contiguous to the side panels 11 and to extend toward transverse partition members 29 with bracing and reinforcing effect. When the tuck-in end panels 22 are thus fully entered into the box interior, the top panels 21 will be brought into horizontal plane in extension over and in closing relation to the upwardly open top of the box, thus arranging the box in fully closed condition.

A novel means unitary with the box structure is provided for interlocking the side flaps of the tuck-in end panels with the side panels of the box structure, whereby to retain the outer end

and top panels and said tuck-in end panels against displacement from their box closing positions, and secure against accidental opening of the box. To this end, the side panels 22 are provided, in portions thereof to which the side flaps 23 of the tuck-in end panels 22 are contiguous when the box is closed, with rectangular locking tongues 35 struck out from the bodies thereof. Each locking tongue is integrally connected by one end thereof to the body of the side panel from which it springs, so as to swing or turn about such connecting end. The side flaps 23 of the tuck-in end panels 22 are each provided with a rectangular locking tongue receiving opening 36, substantially corresponding in dimensions and area to the dimensions and area of the locking tongue 35. Said receiving openings 36 are so located in said side flaps 23 as to be respectively brought into aligned registration with the respective locking tongues 35, when the tuck-in end panels and their said side flaps are disposed in box closing positions. After the tuck-in end panels and their side flaps are disposed in box closing positions, to lock the box against opening said locking tongues are merely pushed inwardly to swing the same through the adjacent receiving openings 36 (see Fig. 8 more particularly). It will be obvious that when thus disposed, said side flaps 23 and tuck-in end panels 22 will be secured against withdrawal or outward movement from the box interior, by reason of the obstruction to such movements offered by the intersecting disposition of the locking tongues across the planes of said side flaps 23.

When the body is made in the form adapted to be divided transversely and thus separated into individual units of smaller or half size, the line of weakening perforations 34 is provided to extend across the bottom and side panels 10 and 11. When the box is set up, packed and closed, in the manner above described, said line of weakening perforations 34 is disposed to extend between the inserted tuck-in end panels 22. When it is desired to divide the box into two separate units, the same is broken apart along said line of weakening perforations 34 (see Fig. 9) thus producing two individual yet nevertheless fully closed boxes. If the cooperating locking tongues 35 and securing openings 36 are utilized, it will be noted that each individual box will also be locked securely against accidental opening.

From the above description, it will be evident that the present invention provides a novel construction of foldable compartment box which may be furnished either as a single unit or in a two-in-one form; in addition, owing to the novel form and relationship of its parts, a box of exceedingly strong and durable construction is provided, wherein the box corners especially are strongly braced and reenforced against collapse, distortion or breakage; and finally wherein the novel arrangement of interior interlocking partition members not only furnish a plurality of goods storage compartments, but also further reinforce and strengthen the box against collapse or breakage.

Having now described my invention, I claim:

1. A foldable compartment box formed from a blank of sheet material and comprising a bottom panel and side panels, each side panel having longitudinal partition members extending from each end thereof including an intermediate spacer section, said spacer sections and longitudinal partition members being adapted to be infolded to dispose the latter within the box interior in

spaced parallel relation to the side panels and so that said spacer sections cooperate with said side panels to form closed box end corners, transverse partition members adapted to be engaged with and across said longitudinal partition members between said side panels, a relatively foldable, longitudinally sequential, arrangement of outer end panel, top panel and tuck-in end panel extending from each end of said bottom panel, each said tuck-in end panel having side flaps laterally extending therefrom, each said arrangement being adapted to be in-folded so that the outer end panels respectively close the opposite exterior box ends and the top panels close the box top with said tuck-in end panels inserted within and through the box interior in face to face relation to extend perpendicularly to the bottom panel between opposed inner ends of said inturned longitudinal partition members and transversely between said side panels and with said side flaps of the tuck-in end panels extending inwardly therefrom to lie contiguous to the side panels, whereby to form closed corners intermediate said tuck-in end panels and side panels, and a line of weakening perforations extending across said side and bottom panels medially of the inserted tuck-in end panels, whereby to permit division of the box, by rupturing said side and bottom panels along said line of perforations, into two completely closed box units.

2. A foldable compartment box formed from a blank of sheet material and comprising a bottom panel and side panels, each side panel having longitudinal partition members extending from each end thereof including an intermediate spacer section, said spacer sections and longitudinal partition members being adapted to be infolded to dispose the latter within the box interior in spaced parallel relation to the side panels and so that said spacer sections cooperate with said side panels to form closed box end corners, transverse partition members adapted to be engaged with and across said longitudinal partition members between said side panels, a relatively foldable, longitudinally sequential, arrangement of outer end panel, top panel and tuck-in end panel extending from each end of said bottom panel, each said tuck-in end panel having side flaps laterally extending therefrom, each said arrangement being adapted to be in-folded so that the outer end panels respectively close the opposite exterior box ends and the top panels close the box top with said tuck-in end panels inserted within and through the box interior in face to face relation to extend perpendicularly to the bottom panel between opposed inner ends of said inturned longitudinal partition members and transversely between said side panels and with said side flaps of the tuck-in end panels extending inwardly therefrom to lie contiguous to the side panels, whereby to form closed corners intermediate said tuck-in end panels and side panels, means to secure said side flaps to contiguous portions of said side panels, and a line of weakening perforations extending across said side and bottom panels medially of the inserted tuck-in end panels, whereby to permit division of the box, by rupturing said side and bottom panels along said line of perforations, into two completely closed box units.

3. A double compartment box formed from a blank of sheet material and comprising a bottom panel and side panels, each side panel having foldable partition forming members extending from each end thereof, and a relatively foldable,

longitudinally sequential, arrangement of outer end panel, top panel and tuck-in end panel extending from each end of said bottom panel, each tuck-in end panel having side flaps laterally extending therefrom, each said arrangement being adapted to be in-folded so that the outer end panels respectively close the box ends and the top panels close the box top with said tuck-in panels inserted within to stand perpendicularly across the medial portion of the box interior in face to face relation and the side flaps thereof disposed to overlie interior surface portions of said side panels, and a line of weakening perforations extending across the bottom and side panels medially of the inserted tuck-in end panels, whereby to permit division of the box, by rupturing said side and bottom panels along said line of perforations, into two completely closed units.

4. A double compartment box formed from a blank of sheet material and comprising a bottom panel and side panels, each side panel having foldable partition forming members extending from each end thereof, and a relatively foldable, longitudinally sequential, arrangement of outer end panel, top panel and tuck-in end panel extending from each end of said bottom panel, each tuck-in end panel having side flaps laterally extending therefrom, each said arrangement being

adapted to be in-folded so that the outer end panels respectively close the box ends and the top panels close the box top with said tuck-in panels inserted within to stand perpendicularly across the medial portion of the box interior in face to face relation and the side flaps thereof disposed to overlie interior surface portions of said side panels, means to secure said flaps to contiguous portions of said side panels, and a line of weakening perforations extending across the bottom and side panels medially of the inserted tuck-in end panels, whereby to permit division of the box, by rupturing said side and bottom panels along said line of perforations, into two completely closed independent box units.
